CLAIM

The ornamental design for a bowl for a micro puree machine, as shown and described.

DESCRIPTION

FIG. 1 is a top/front view of an embodiment of a bowl of our design;

FIG. 2 is a front view of the bowl;

FIG. 3 is a rear view of the bowl;

FIG. 4 is a right side view of the bowl;

FIG. 5 is a left side view of the bowl;

FIG. 6 is a top view of the bowl; and,

FIG. 7 is a bottom view of the bowl.

In the drawings, the broken lines depict portions of the bowl which form no part of the claim.

1 Claim, 7 Drawing Sheets

Related U.S. Application Data

continuation-in-part of application No. 17/139,660, filed on Dec. 31, 2020, now Pat. No. 11,925,298.
